ACOUSTICAL HEADBAND

Blaise Calame, 8 rue Gay-Lussac, Paris, France

Filed Sept. 25, 1973, Ser. No. 400,510

Claims priority, application Sweden Mar. 26, 1973

Term of patent 14 years

Int. Cl. D2—03

U.S. Cl. D2—259

FIG. 1.

FIG. 2.

FIG. 3.

FIG. 5.

FIG. 4.

FIG. 1 is a front elevational view of an acoustical headband showing my new design;

FIG. 2 is a top plan view taken along the line 2—2 of FIG. 1;

FIG. 3 is a side elevational view taken along the line 3—3 of FIG. 2; the other side being a mirror image thereof;

FIG. 4 is a rear elevational view taken along the line 4—4 of FIG. 3; and

FIG. 5 is a bottom plan view taken along the line 5—5 of FIG. 4.

I claim:

The ornamental design for an acoustical headband, substantially as shown and described.
